UNITED STATES PATENT OFFICE

HENRY RABES, OF WASHINGTON, DISTRICT OF COLUMBIA, ASSIGNOR, BY MESNE ASSIGNMENTS, TO CHAIN STORE PRODUCTS CORPORATION, OF CHICAGO, ILLINOIS, A CORPORATION OF DELAWARE

HAIR WAVER

Application filed June 28, 1928, Serial No. 288,915. Renewed July 21, 1930.

The present invention relates to devices for waving hair, and consists of a core portion around which the hair is wrapped, in combination with hair waving portions cooperating therewith and pressing the wound hair into wave form.

An object of the invention is to provide a simple device for the foregoing purpose which will accomplish the waving of hair in a few minutes' time and without the application of heat.

A further object of the invention is to provide a unitary device of the above character without detachable parts.

A still further object is to provide such a device which accomplishes the waving of hair as distinguished from merely curling it.

Other and further objects of the invention will appear from the following description taken in connection with the accompanying drawings which illustrate a preferred embodiment of the invention and in which:

Figure 1 is a perspective view of a hair waver embodying the present invention;

Figure 2 is a transverse vertical sectional view through the central portion of Figure 1;

Figure 3 is a top plan view of the hair waver; and

Figure 4 is a perspective view thereof with the hair pressing portions in open position, preparatory to winding hair about the core.

Referring in detail to the accompanying drawings, the present invention includes a forming element provided with separate grooves in which hair is forced into a waving outline by means of presser or forming members cooperating with the grooved core.

Accordingly, in the present example of the invention herein shown by way of illustration, the core 11 is shown as comprising a plurality of radially extending flanges 12 providing a groove 15 between each two adjacent flanges. In the present example of the invention four flanges are shown, thus providing four grooves, and in the present case, the flanges 12 extend radially, 90 degrees apart.

In practising the invention, hair is wound loosely about the core 11 and is pressed into

the grooves 15 by presser members. In the present embodiment of the invention these presser members have the form of wire loops 18 passing through holes 19 formed near the ends of two diametrically opposite flanges 12. The presser members are adapted to straddle the flange to which they are pivotally attached, and thus each presser member functions to press hair into two adjacent grooves. An important advantage of this construction is that each presser member cooperates with two grooved portions.

For the purpose of holding the presser members in operative position, each is formed with sufficient spring tension to ride over a hump 19 on the end of the flange 12 to which the presser member is pivotally attached, thence down into a slight depression 20, where the presser members 18 are held in pressing position.

It will be seen from Figure 1 that hair waved on the device of the present invention, when released, has a form resembling the outline of a sine wave, that is, first above and then below a central axis.

It is obvious that presser members of other form may be attached to the core to press hair down into the grooves 15 without departing from the present invention, and that other changes may be made without departing from the scope of the invention as defined in the following claims.

What is claimed is:

1. A hair waver comprising a core having flat flanges extending radially from a center line and forming grooves therebetween, a loop member pivoted to each of two oppositely extending flanges for pressing hair into the grooves between the flanges and each adapted to straddle the flange to which it is pivoted, and hump means on each flange to which a loop member is pivoted cooperable with said loop member to retain it in hair pressing position.

2. A hair waver comprising a core having flanges extending outwardly from a center line and forming grooves therebetween, a loop member movably connected to each of two oppositely extending flanges for pressing hair into the grooves between the flanges and

each adapted to straddle the flange to which it is movably connected, and means on each flange to which a loop member is pivoted co-operable with said loop member to retain it in hair waving position.

3. A hair waver comprising a core having flanges extending outwardly from a center line and forming grooves therebetween, a loop member pivoted to one of said extending flanges for pressing hair into the grooves between the flanges and adapted to straddle the flange to which it is pivoted, and means on said flange co-operable with said loop member to retain it in hair pressing position.

15 15. In testimony whereof I affix my signature.
HENRY RABBES.
